UNITED STATES PATENT OFFICE.

RILEY A. STUBBS, OF GREENVILLE, OHIO.

BOLTING-REEL.

SPECIFICATION forming part of Letters Patent No. 427,277, dated May 6, 1890.

Application filed March 23, 1889. Serial No. 304,426. (No model.)

To all whom it may concern:

Be it known that I, RILEY A. STUBBS, of Greenville, in the county of Darke and State of Ohio, have invented a new and Improved 5 Bolting-Reel, of which the following is a full, clear, and exact description.

The object of the invention is to provide a new and improved bolting-reel which is simple and durable in construction, very effective in operation, preventing the accumulation of flour in the hopper, and also preventing any leakage from the gates.

The invention consists in certain parts and details and combinations of the same, as will be 15 fully described hereinafter, and then pointed out in the claims.

Reference is to be had to the accompanying drawings, forming a part of this specification, in which similar letters of reference indicate 20 corresponding parts in all the figures.

Figure 1 is an end elevation of the improvement. Fig. 2 is a longitudinal vertical section of the same on the line $x-x$ of Fig. 1. Fig. 3 is a transverse section of the same on 25 the line $y-y$ of Fig. 2; and Fig. 4 is a sectional plan view of a part of the improvement.

The improved bolting-reel is provided with a suitably-constructed casing A, in which is mounted to turn the reel B, provided with the 30 heads C and D, of which the former has an outwardly-projecting hub C', having a conical opening C², largest on the inside, as shown in Fig. 2. The hub C' is mounted to turn in one end A² of the casing A and projects to 35 the outside, and between the said end A² of the casing and the head C is placed a suitable packing C³, surrounding the hub and held in place by a ring C⁴ on the head C, so as to make the joint of the hub C' and the end A² dust-proof. On the other head D is secured 40 a shaft D', extending outward and mounted to turn in suitable bearings A', formed on the end of the casing A. On the outer end of the said shaft D' are held the usual fast and loose 45 pulleys, connected with suitable machinery for imparting a rotary motion to the reel B.

In the head D, near its periphery, are arranged a number of openings D³, which lead to the interior of the casing A and serve to 50 discharge the tailings. On each of the heads C and D are secured by bolts or other suitable means two half-rings E, on each of which

are cast or otherwise secured the longitudinally-extending bars E', on which the cloth E² is secured, either on the inside or on the 55 outside, as desired. It is understood that the support for the cloth E² is thus made of two parts, each comprising two half-rings located opposite each other on the heads C and D and connected with each other by the bars E'. 60

In the outer narrow end of the hub C' is fitted a feed-block F, secured to a band F', fastened on the end A² of the casing A. In the block F is formed a downwardly-extending aperture F², to the outer end of which is 65 connected the usual spout for discharging the material to be bolted. The material passing through the spout into the opening F² passes from the latter into the conical openings C² of the hub C', and from the latter passes into 70 the interior of the reel.

The outer end of the hub C' is supported on two friction rollers or wheels G and G', mounted on studs G², secured on a plate G³, fastened to the outside of the end A² of the 75 casing A. The wheels G and G' thus relieve the packing C³ from any pressure, at the same time forming a convenient bearing for the hub C'.

In the casing A below the reel B are arranged the usual longitudinally-extending inclined sides H and H', forming a hopper, the lower end of which is open and connected with a cut-off I, comprising a number of gates J, all of the same construction and placed 85 alongside each other, being mounted to turn on a rod K, extending longitudinally and passing through the ends A² and A³ of the casing A. On the outer end of the rod K screw the nuts K', against which presses a coil-spring K², 90 also pressing against the end gates J, so as to hold the several gates in firm contact with each other to prevent flour from passing between the gates.

Each of the gates J is provided with a 95 straight part J', adapted to register at its ends alternately with the longitudinal sides H and H', forming the hopper, as is plainly shown in Fig. 3. Each part or bar J' is formed on a semicircular part J², mounted to 100 turn in a correspondingly-shaped bearing L, located centrally in the casing A and extending longitudinally thereon from one end to the other. The top of the bearing L is pro-

vided with a suitable lining L' , serving to make a tight joint between the bearing and the semicircular part J^2 . The gates J are very narrow, so as to give the operator a chance to cut off at any desired point throughout the length of the reel.

The lower ends of the bars J' are adapted to discharge into the conveyer-boxes N and N' , provided with the usual mechanism for removing the accumulated flour. In the casing A are arranged two dividing-frames O and O' , through each of which the reel B passes, and each is provided with two sets of rollers P and P' , mounted to travel on a bar Q , extending longitudinally in the casing A and fastened to the ends of the same. On the lower end of each dividing-frame O and O' are secured downwardly and outwardly extending arms R and R' , extending in opposite directions and slightly diverging, as plainly shown in Figs. 2 and 4, so that the lower end of each arm extends onto the next following gate J . The angle of the arms R and R' corresponds with the angle of the bars J' , so that the said arms rest on the said bars.

When the operator desires to shift the gates J , he takes hold of the lower end of the bar J' and swings the same upward, so that the gate turns on its bearing L and the rod K . When the operator takes hold of the bar J' of the gate J , located under the arm R or R' , and moves the same upward, said arm R or R' is engaged by the respective gate and is moved longitudinally, whereby the dividing-frame O or O' travels longitudinally in the casing A , thereby shifting its position. Thus the operator is enabled to shift the dividing-boards to any desired position and to place as many gates J in such a position as to discharge into either conveyer-box N or N' , as he desires.

As illustrated in Fig. 2, the fifteen middle gates J discharge into the conveyer-box N' , while the remaining end gates discharge into the conveyer-box N , and when the operator desires to increase the middle gates on the left he moves the gate directly under the arm R upward, whereby the said gate assumes the same position as the middle gates, and at the same time the dividing frame or board O is moved to the left a distance equal to the width of one gate. In a like manner, when the operator desires to increase the number of gates on the right-hand end, he moves the last of the middle gates on the right so as to discharge into the conveyer-box N , whereby the said gate engages the arm R' of the dividing-board O' and moves the same to the left. In this manner any desired number of gates may be shifted, at the same time the dividing-boards O and O' changing their relative position, according to the number of gates shifted.

The operation is as follows: The material to be bolted is passed through the opening F^2 in the block F and through the hub C' into the interior of the reel B , which receives its

usual rotary motion from the driving-pulley on the shaft D' . The flour passing through the cloth E^2 falls into the hoppers H and H' , and from the latter is discharged onto the gates J , which deliver the bolted material into the conveyer-boxes N and N' , according to the arrangement of the gates J . It will be seen that the accumulation of flour under the reel is prevented by the special arrangement of the gates with the inclined walls H and H' . It will further be seen that any leakage between the gates J is prevented, as the latter are placed in firm contact with each other by the tension of the springs K^2 . Said springs also take up any side wear between the several gates, as well as any shrinkage or swelling, so that a tight joint is always made between the several gates. The forward-and-backward motion of the dividing-boards O and O' is rendered very easy, as the said boards are supported and travel on the longitudinally-extending beam Q .

Having thus described my invention, what I claim as new, and desire to secure by Letters Patent, is—

1. In a bolting-chest, the combination, with a hopper open at its lower end, of gates mounted to turn below the said hopper and adapted to register at their ends with lower edges of the hopper-sides, substantially as shown and described.

2. In a bolting-chest, the combination, with the sides of the hopper, of gates mounted to turn below the said hopper and each comprising a straight bar adapted to register at its ends with the lower edges of the said sides, and a semicircular offset carrying the said bar and fitted to turn in suitable bearings, substantially as shown and described.

3. In a bolting-chest, a series of gates placed alongside each other and each comprising a bar and semicircular part carrying the said bar and mounted to turn, substantially as shown and described.

4. In a bolting-chest, a series of gates placed alongside each other and each comprising a bar and semicircular part carrying said bar and mounted to turn, and a rod passing through the centers of the said circular parts and forming the pivot for the same, in combination with a dividing-board operated by said circular parts, substantially as shown and described.

5. In a bolting-chest, a series of gates placed alongside each other and each comprising a bar and semicircular part carrying said bar and mounted to turn, in combination with a rod passing through the centers of the said circular parts and forming the pivot for the same, and springs pressing against the gates located at the ends, so as to form a tight joint between the several gates, substantially as shown and described.

6. In a bolting-chest, a series of gates placed alongside each other and each comprising a bar and semicircular part carrying the said bar and mounted to turn, in combination

with dividing-boards mounted to travel longitudinally and actuated by the said gates, substantially as shown and described.

7. In a bolting-chest, a series of gates placed alongside each other and each comprising a bar and semicircular part carrying the said bar and mounted to turn, in combination with dividing-boards mounted to travel longitudinally and each provided with two inclined arms extending over the bars of the said gates and actuated by the same, substantially as shown and described.

8. In a bolting-machine, the combination, with the reel, of transverse dividing-boards through which passes freely the said reel, and a fixed rail on which the said dividing-boards are mounted to travel longitudinally, substantially as shown and described.

9. In a bolting-machine, the combination, with the reel, of transverse dividing-boards through which passes freely the said reel, a fixed rail on which the said dividing-boards are mounted to travel longitudinally, and gates held below the said dividing-boards and adapted to actuate the same, substantially as shown and described.

10. In a bolting-machine, the combination, with the reel, of transverse dividing-boards through which passes freely the said reel, a fixed rail on which the said dividing-boards are mounted to travel longitudinally, and friction-wheels mounted on the said dividing-boards and traveling on the said rail, substantially as shown and described.

11. In a bolting-machine, the combination, with the casing having inclined hopper-sides, of a reel mounted to turn in the said casing, transversely-extending dividing-boards through which passes the said reel, and a series of gates held below the said dividing-boards and adapted to actuate the same, substantially as shown and described.

12. In a bolting-machine, the combination, with the casing having inclined hopper-sides,

of a reel mounted to turn in the said casing, transversely-extending dividing-boards through which passes the said reel, a series of gates held below the said dividing-boards and adapted to actuate the same, and a longitudinally-extending rail secured in the said casing and on which the said dividing-boards are mounted to travel, substantially as shown and described.

13. In a bolting-machine, the combination, with the casing having inclined hopper-sides, of a reel mounted to turn in the said casing, transversely-extending dividing-boards through which passes the said reel, a series of gates held below the said dividing-boards and adapted to actuate the same, and friction-wheels held on the said dividing-rail, substantially as shown and described.

14. In a bolting-machine, the combination, with the casing having inclined hopper-sides, of a reel mounted to turn in the said casing, transversely-extending dividing-boards through which passes the said reel, and a series of gates held below the said dividing-boards and adapted to actuate the same, and conveyers located below the said gates at each side thereof, substantially as shown and described.

15. In a bolting-machine, the combination, with the casing having inclined hopper-sides, of a reel mounted to turn in the said casing, transversely-extending dividing-boards through which passes the said reel, a series of gates held below the said dividing-boards and adapted to actuate the same, conveyers located below the said gates at each side thereof, and a lined bearing formed on the top of the partition of the said conveyers and fitted against the underside of the said gates, substantially as shown and described.
